(74) Attorney, Agent, or Firm — Bookoff McAndrews,
 PLLC

(57) **CLAIM**

The ornamental design for a display screen with graphical user interface, as shown and described.

DESCRIPTION

The single FIGURE is a front view of a display screen with graphical user interface showing our new design. The outer broken line perimeter showing the display screen forms no part of the claimed design. The broken line showing of text and elements forms no part of the claimed design.

1 Claim, 1 Drawing Sheet
